UNITED STATES PATENT OFFICE

HAROLD A. DENMIRE, OF AKRON, OHIO, ASSIGNOR TO THE GENERAL TIRE & RUBBER COMPANY, OF AKRON, OHIO, A CORPORATION OF OHIO

WATCHCASE HEATER

Application filed March 7, 1927. Serial No. 173,300.

This invention relates to watch case heaters and it has for one of its objects, the provision of a greatly simplified and improved type of heated for particular use in the rubber industry.

Another object of the invention is to provide a hydraulically actuated watch case heater wherein adequate closing pressure can be obtained for curing either solid or hollow articles therein without the use of undesirably high liquid pressures.

A further object of the invention is to provide a watch case heater wherein the mold units may be easily and quickly changed without removal of the mold shells from the associated steam jacket.

Another object of the invention is to provide a watch case heater wherein the assembled mold units are removably supported from the hydraulic unit.

An additional object of the invention is to provide a watch case heater wherein the door of the heater is closed by the direct pull of a hydraulic piston of greater diameter than the internal diameter of the molding cavity.

Other objects and advantages to be derived from practicing the invention will be apparent to those skilled in the art.

Preferred embodiments of the invention are shown in the accompanying drawings wherein:

Figure 1 is a front elevational view of a watch case heater embodying the invention.

Fig. 2 is a side elevational view of the heater shown in Fig. 1.

Fig. 3 is a horizontal sectional view of the heater shown in Figs. 1 and 2, taken substantially on line 3—3 of Fig. 1.

Fig. 4 is a corresponding horizontal sectional view of a modified form of heater embodying the invention.

The embodiment of the invention shown in Figs. 1, 2 and 3 comprises a heater body 1 that has a suitable supporting pedestal 2 and two sets of oppositely extending supporting brackets 3 and 4 that respectively removably support watch case heater units 5 and 6.

The heater body 1 has a pair of opposed cylinders 7 and 8 formed therein. Each cylinder is closed at its outer end by a cylinder

head 9 that has a suitable packing gland 10 through which a piston rod 11 extends. The inner end of each cylinder is closed, if desired, by a partition 12, or the same cylinder may be used for both pistons as set forth in my prior application Serial No. 139,485, filed Oct. 4, 1926, and is entitled "Watch case heater". A suitable piston 13 is mounted in each cylinder to be acted on by hydraulic pressure applied between the cylinder head and the piston. Pressure, preferably air, that is applied between the partition 12 and the respective pistons 13 serves to move the pistons to their outermost positions, thus permitting the molds to be opened by release of the mold door from the piston.

The heater body 1 also has a pair of spaced annular flanges 14 and 15 extending outwardly therefrom that are connected at intervals by suitable reinforcing webs 16. The mold units 5 and 6, although preferably supported from the brackets 3 and 4 that are respectively formed on the cylinder heads, are secured in place by stud bolts 17. Heat insulating plates 18 and 19 that are capable of withstanding the hydraulic pressure imposed upon the mold units, provide seating faces for the mold units. The supporting brackets 3 and 4 each comprise a plurality of radially arranged webs that engage the inner face 20 of one of the mold sections.

The mold sections 21 and 22 that are hinged together by a pintle 23, together form the watch case mold unit 5 that is supported from the bracket 3. Each mold section preferably has a steam cavity 24 by means of which the mold is heated for the vulcanization or curing of rubber articles placed therein. The molding face 25 or mold shells of each mold section may be integral with the steam jacket 26 or removably connected thereto in accordance with conventional practice. One of the mold sections preferably has an annular seating lug 26 formed thereon for receiving the securing stud bolts 17. The other mold section has a pair of opposed pressure lugs 27 formed thereon and adapted to receive the hydraulic pressure applied to the corresponding piston through the piston rod 11 and the rotatable connecting head 28, thereby serv-

ing to close the mold with great pressure. The hinge pintles are sufficiently loose in one of the mold sections to permit complete closing of the mold units. Any suitable means is employed for causing the mold sections to properly register. Each mold section also preferably has a lifting ring 29 by means of which the mold units may be lifted and removed or mounted on the supporting base.

10 The operation of the heater will be obvious to those skilled in the art. The mold unit is brought to position on the supporting brackets 3 or 4 and the stud bolts 17 are tightened up to hold the mold unit in place. The 15 steam jackets are then connected with the heating fluid. The mold cavity is charged and the mold door closed. The connecting head 28 is turned to engage the opposed lugs 27 and hydraulic pressure is applied between the corresponding cylinder head and piston. 20 Steam or other heating fluid is then admitted to the steam cavities 24 of the mold until the cure is completed. The hydraulic pressure is then released and air under pressure is 25 introduced between the piston and the cylinder partition to move the piston to its outermost position. The connecting head 28 is then turned and the mold opened.

It will readily be seen from the preceding 30 description that the hydraulic pressure is directly applied to the mold; that the mold units are readily and quickly removable; that the operation of the unit depends upon the speed with which materials may be introduced into the molding cavity; that any desired molding pressure can be obtained; and that the dangers of jamming mechanical parts 35 and thus preventing complete closure of the molds are obviated.

40 The mold unit shown in Fig. 4 differs from the previously described unit principally in the manner of supporting the mold unit from the hydraulic mechanism. In this form of heater, the cylinder head has a series of supporting web-like brackets 30 that engage the inner face and one lateral face of the mold section. One of the webs is enlarged and recessed to form a seat for a key 31 that engages a suitable keyway of the mold unit to prevent turning of the mold on the support. The 45 outer ends of the webs are connected by an annular flange 32 of the cylinder head. The spaces between the cylinder head and the supporting faces of the mold units may be filled in with any suitable heat insulating material, to prevent undesirable conduction of heat from the mold unit to the hydraulic unit. This mold unit does not require any 55 securing lugs and is very fast to remove and mount in place.

60 Many of the advantages inherent in this proposed heater will be apparent to those skilled in the art. The operation of the heater is much faster than those previously proposed and the dangers of incompletely closed

molds from the jamming of mechanical parts is avoided. The saving in the expense of manufacture of the heater is also very large because of the simplified mechanical construction proposed. Any desired size of piston 70 can be used without regard to the internal diameter of the mold and the advantages of a straight line hydraulic pull between the piston and the mold door are obtained. It is also important that the hydraulic mechanism 75 may be thermally insulated from the heating jackets of the mold units thereby preventing undue sweating of the hydraulic parts with resulting damage to the molded materials and enabling cold water to be used for 80 obtaining hydraulic pressure.

85 Although only preferred embodiments of the invention are specifically described, other heater structures embodying the invention will be apparent to those skilled in the art and I desire, therefore, that the invention be protected as broadly as the prior art will permit.

What I claim is:

90 1. A watch case heater comprising a base having a hydraulic cylinder therein with opposed pistons mounted therein and piston rods extending through the cylinder heads, and assembled mold units composed of separable sections and removably mounted on said base, and means carried by the piston rods and engageable with the outer of the mold sections to close the mold.

95 2. A watch case heater comprising a base having a cylinder arranged transversely thereof, a pair of opposed pistons mounted within the cylinder, outwardly opening hinged molds secured to opposite sides of the base and releasably engageable with said pistons whereby closing pressure is applied 100 to said molds, said pistons being of greater diameter than the minimum diameter of the molding cavities of the molds.

105 In testimony whereof I affix my signature.

HAROLD A. DENMIRE.
